Inventor,
Irvin J. Fernekes

UNITED STATES PATENT OFFICE.

IRVIN J. FERNEKES, OF CHICAGO, ILLINOIS.

RAILROAD-SWITCH CONTROL.

Application filed March 19, 1921. Serial No. 453,547.

To all whom it may concern:

Be it known that I, IRVIN J. FERNEKES, a citizen of the United States, residing at Chicago, in the county of Cook and State of Illinois, have invented certain new and useful Improvements in a Railroad-Switch Control, of which the following is a specification.

This invention relates to the operation of railroad switches from the locomotive cab or any other part of a train of cars without stopping the train and without the operator alighting from the train to throw the switch.

Among the objects of the invention are:

- 10 To provide means for indicating in advance of the switch the condition thereof; to electrically operate the switch in advance or after the switch is passed from a fixed point in the train without stopping the train; to
- 20 utilize the same apparatus for opening and closing the switch; to operate an indicating target or signal upon the operation of the switch which will show the condition of the switch at a plurality of points; to provide
- 25 suitable switch operating mechanism electrically controlled for operating the switch and for operating one or more indicating targets; to operate one of a plurality of switches from any one of a plurality of train
- 30 positions; and in general, to provide a switch controlling system having the construction, combination and arrangement of parts as herein set forth.

In the accompanying drawings, Fig. 1 is a diagrammatic representation of a switch control system of this class as applied to a main track and a siding therefor; Fig. 2 illustrates the method of applying an energizing electric current to the contact rails located

- 40 between the other rails of a track; Figs. 1^a and 1^b illustrate modifications of the signal switch and the devices controlled thereby; Fig. 3 is a sectional view showing a switch operating construction and a signal therefor; and Fig. 4 is a diagrammatic view showing a circuit closing means operated by the switch motor for controlling the indicating targets.

In this switch control system the contact rails are disposed on both sides of the switch to be controlled thereby and if desired, at a plurality of points on each side thereof so that the switch can be controlled in either direction of travel to accommodate a train of any length. The application of this will be quite apparent, and although the present

invention is described as applied to a main track and a siding with a switch at either end of the siding, it is obvious that the same system may be employed in ladder and yard tracks of any kind. To separately control the track switches at opposite ends of the siding, three contact rails are provided in the siding, one rail being used in common with either of the other two to control either

60 65

track switch. Referring now more particularly to the drawings, a main track 1 has a siding 2 connected thereto by switches 3 at the ends of the siding. Between the rails of the main track at some distance beyond one end of the siding are contacts 4 and 5, and beyond the switch at the other end of the siding are contacts 4 and 6. Corresponding contact rails 4, 5 and 6 are also positioned between the rails of the siding in a plurality of spaces usually adjacent the ends of the siding and near the switches 3, although they may be at any desired points depending somewhat upon the length of the siding. Likewise the pairs of contacts 4 and 5 or 4 and 6 at either end of the siding may be duplicated at different distances therefrom, but one pair at each end is sufficient to illustrate the present invention. The contacts in the main track are usually at such a distance from the track switch which they control that the switch will be opened before the train reaches the switch even though it is travelling at a fairly good rate of speed. A train usually slows up for a switch and the contact rails are of sufficient length to apply an electric current thereto from the train for operating the switch and signal mechanism. After the track switch is operated the current is cut off.

80 85 90 95

Contact rails 4 are all connected to a trunk conductor 7, rails 5 to a trunk conductor 8, and rails 6 to a trunk conductor 9. These trunk conductors are properly carried by a pole line at the side of the track or in any other suitable way so they are insulated from each other.

Adjacent each pair of contact rails in the main track is an indicating signal 10 preferably of the dwarf signal type, but clearly visible from the train. It may comprise a single arm 11 as well as a lamp 12 of any ordinary indicating type to show the condition of the switch 3 at night as well as by day. A signalling device of this kind may also be located adjacent the siding contacts

105 110

as indicated in broken outline in Fig. 1, connected in parallel with the other signal 10, but ordinarily the siding signal is not necessary.

- 5 At each switch 3 is a switch mechanism, as shown more clearly in Fig. 3 which comprises an ordinarily fixed signal stand 13 carrying a lamp signal 14 and target arms 15. In a box or receptacle 16 at the base 10 of the stand is an electric motor 17 of the reversible type which has a pinion 18 meshing with an elongated gear 19 and also engaging a gear 20 at the bottom of the stand 13 for rotating the switch stand to 15 indicate clear or danger. The gear 19 is mounted on a bar or shaft 21 which extends through a fixed and internally threaded box 22. Affixed to the shaft is a threaded member 23 which engages the threads of the 20 box 22 so that the rotation of the gear 19 moves the shaft and with it the gear 19 longitudinally. At the outer end of the shaft 21 it is connected by means of a bracket 24 to the opposite switch points 25 25 and 26 which are joined by a cross connection 27. In order to permit the rotation of the shaft where it joins the track 24, an enlarged head 28 is provided which engages in a box 29 connected to the bracket. 30 A nut or gear 30 may be provided on the shaft 21 outside of the receptacle 16 for rotating the shaft in an emergency in case the motor 17 should fail to operate the switch. 35 At the inner end of the shaft 21 is an electric switch 31 preferably of the knife blade type, comprising an arm 32 having a pin and slot connection 33 with the shaft for operating the switch with a lost motion 40 movement depending upon the direction of longitudinal movement of the shaft. This switch 31 is intended to control the operation of the signal devices 10 after the 45 operation of the switch itself and the lost motion connection is to insure that the switch will be operated before the signal 10 therefor is operated to insure that the switch is in the position indicated.
- In order to energize and to reverse the 50 switch motors 17 and the other electric devices a source of current supply 34 is provided in the locomotive cab or in any of the train cars, which is connected through a reversing switch 35 to the spring pressed 55 contact shoes 36 which engage the contact strips or rails 4, 5 and 6 between the tracks. In making these connections one of the contacts of switch 35 is connected by a conductor 37 to one of the contact shoes 36. 60 The other switch contact is connected by a conductor 38 to a switch arm 39 which engages a contact 40, in one direction of movement and a contact 41 in the other direction of movement. The contact 40 is connected by a conductor 42 to the contact shoe

36 for the middle contact strip 6, and the contact 41 is connected by a conductor 43 to the other contact shoe 36 for the contact strip 5.

In operating the train portion of this apparatus, the arm 39 is moved to engage either contact 40 or 41 depending upon the track switch which it is desired to operate, and the reversing switch 35 is operated to "open" or "close" position, depending upon 75 whether it is desired to open or close the selected track switch.

As shown in Fig. 4, the operation of switch 31 in one direction closes a connection from the trunk wire 8 and conductor 80 44 through the switch arm 32 to contact 45 and thence by conductor 46 to the signal 10 and from the signal 10 back to the other trunk line 7. The engagement of the track contacts 4 and 5 by the contact shoes of 85 the train apparatus will permit a current to be closed in either direction to the motor 17 which will subsequently energize the signal 10 by the operation of the switch 31 just described.

In either case, the signal 10 receives current only when the shaft 21 is at one end of its longitudinal movement.

By connecting both contacts 45 and 47 of the switch 31 with a conductor 48 and then connecting this conductor to the conductor 46, as shown in Fig. 1^a, the switch 10 will be energized at each end of movement of the shaft 21. If desired, both a lamp 49 and a motor 50 may be included 100 in the conductor line 46 and the lamp will be lighted and the motor will be energized oppositely at each end of movement of the shaft 21. The motor 50 may be replaced by a magnet or any other suitable electro 105 magnetic device, if it is desired to operate a signal arm 11.

Instead of the arrangement illustrated in Fig. 1^a, separate conductors 51 and 52 may be connected to the contacts 45 and 47 110 of the switch 31 and an electric lamp 53 and a magnet 54, or other electro responsive devices may be connected in each branch, the two branches being connected by the conductor 46, as before explained, 115 to the trunk conductor 7. It should be understood that these lamps 53 and magnets 54 are a part of the dwarf signal 10 and are for operating the visual and indicating means thereof to show the position of 120 the track switch to which the dwarf signal relates.

In any case the switch arm 32 is operated between the switch contacts 45 and 47 by 125 the movement of the track switch and the shaft 21, as shown and described in connection with Figs. 3 and 4.

In operation let us suppose that a train is approaching the siding from the right hand end of Fig. 1. The dwarf signal 10 adjacent 130

the contact strips 4 and 6 will indicate the condition of the track switch ahead. If the engineer wishes to continue on the main track no operation is necessary; if he wishes to go on the siding he first throws the switch arm 39 so that it makes contact with the outer strip contact 41 and then throws the blade operator of switch 35 to the open position which connects the contact shoes 36 with the contact strips 4 and 6, and thence through trunk line conductors 7 and 9 to operate first the track switch 3 by means of the motor 17, then the dwarf signal switch 31, and finally the dwarf signal itself to indicate that the track switch is in the desired position.

If the siding switch were open it could be closed by the train operator, by simply throwing the switch 35 to close position. In the same way the siding switch 3 at the left hand end of Fig. 1 may be opened or closed from the main track through the track contacts 4 and 5.

When the train is on the siding the switch at either end of the siding can be closed from a plurality of points, and it is preferable to have three contacts at each position, the pairs of contacts 4 and 5 relating to the switch at one end of the siding and the pairs of contacts 4 and 6 relating to the switch at the other end of the siding. In this case it is necessary to move the switch arm 39 to engage either the contact 40 or 41 to connect with the contact strip 6 at the center of the siding or with the other contact strip 5, the connection for the contact strip 4 being common to both pairs of contacts. Thus by engaging the proper track

contacts it is apparent that the switches at both ends of the siding can be controlled from the train at any one of a plurality of places in the siding.

It is apparent that other changes in the construction, combination and arrangement of the several parts may be made without departing from the spirit and scope of the invention.

I claim:

1. In an electric switch control for railroads, the combination with a main track and a siding therefor having an electrically operated switch at both ends, of a pair of track contacts beyond the ends of the siding, means operable from a train to engage the contacts for closing electric connections to operate the switch adjacent thereto, and three or more track contacts in the siding for closing electrical connections to operate either one of the switches from the same position.

2. In a railroad switch control, the combination with a main track and a side track connected thereto by a plurality of electrically operated switches, of a pair of contacts in the main track for controlling the switch adjacent thereto, and three contacts in the siding for controlling the electrically operated switch at either side thereof, one of the contacts being common to each pair of contacts necessary to control one of the switches, and means operable from a train to engage the contacts for closing electrical connections to operate the selected switch without stopping the train.

IRVIN J. FERNEKES.
